UNITED STATES PATENT OFFICE.

EUGENE L. RAGONNET, OF MIAMI, FLORIDA, ASSIGNOR TO AIR REDUCTION COMPANY, INC., A CORPORATION OF NEW YORK.

BLCPPIPE.

1,417,628.

Specification of Letters Patent. Patented May 30, 1922.

Application filed January 13, 1921. Serial No. 436,939.

To all whom it may concern:

Be it known that I, EUGENE L. RAGONNET, a citizen of France, residing at Miami, in the county of Dade, State of Florida, have 5 invented certain new and useful Improvements in Blowpipes; and I do hereby declare the following to be a full, clear, and exact description of the invention, such as will enable others skilled in the art to which it app- 10 pertains to make and use the same.

This invention relates to cutting blowpipes, employing oxidizing and combustible gases such as oxygen and acetylene and utilizing a jet of the oxidizing gas to cut material by oxidation thereof after it has been raised to the ignition temperature by a pre-heating flame or flames. In such blowpipes, three pipes or conduits for the gases are usually provided, one for the combustible gas, 15 another for oxidizing gas which is mixed with the combustible gas to produce the pre-heating flames, and a third which conveys oxidizing gas for the cutting jet. The conduits supplying the heating flames are controlled 20 by manually operable valves to permit regulation. The third conduit in an ordinary two-connection blowpipe receives oxidizing gas from an inlet supplying both oxidizing gas conduits; the flow of oxidizing gas to 25 provide the cutting jet being controlled by a manually operable valve which is capable of rapid manipulation. This arrangement permits the opening and closing of the valve controlling the cutting jet with the facility 30 required in the satisfactory operation of the blowpipe, and it is to the arrangement for controlling the cutting jet valve that the present invention is directed.

It is the object of the invention to pro- 40 vide a simple and inexpensive controlling valve for the cutting jet with operating mechanism so arranged as to insure positive operation with a minimum of effort and deflection of the jet.

45 A further object of the invention is the provision of a cutting blowpipe which may be inexpensively constructed and assembled, and which is free from parts liable to derangement in use, whereby maximum utility 50 and operative life thereof is assured.

Further objects and advantages of the invention will be apparent as it is better understood by reference to the following speci-

fication and the accompanying drawing, in which—

55 Fig. 1 is a side elevation partially in section, illustrating a blow pipe constructed in accordance with the invention.

Fig. 2 is a section on the line 2—2 of Fig. 1.

60 Fig. 3 is a section on the line 3—3 of Fig. 1, and

Fig. 4 is a section on the line 4—4 of Fig. 1.

65 Referring to the drawing, 5 indicates the head of a blowpipe, which is provided with interchangeable tips 6. A nut 7 holds the tip in assembled relation with the head and permits removal and replacement thereof. Oxidizing and combustible gases are sup- 70 plied to suitable passages in the head through pipes or conduits 8, 9 and 10, the conduit 8 carrying acetylene, for example, the conduit 9 carrying oxygen for the heating flames and the pipe 10 carrying oxygen 75 for the cutting jet. The details of the blowpipe head and tips form no part of the present invention and may vary within wide limits; various commercial structures being 80 recognized and approved by those skilled in the art.

85 The conduits 8, 9 and 10 are enclosed at their rear ends within a casing 11, forming the handle of the blowpipe, and the conduit 10 terminates in a block 12 which is secured 90 within the casing, the ends of the conduit being preferably silver soldered into a passage 33 formed in the block. The conduits 8 and 9 may be similarly connected to the block, but conveniently they extend through 95 openings therein and rearwardly thereof to a butt 13, and are secured thereto in communication with passages 14 and 15, controlled by manually operable valves 16 and 17 of the usual type. The butt 13 is pro- 95 vided with nipples 18 adapted for connection with flexible conduits, which deliver the oxidizing and combustible gases to the blow- pipe. A passage 15' by-passes the valve 17 and a conduit 19 provides communication 100 between the passages 15' and passages 20 in the block 12.

105 The block 12 is provided with a valve chamber 21 communicating with the pas- sages 20, and supports a valve housing 22, which is threadedly mounted in the block so

that it may be readily removed when necessary. A piston valve 23 is slidably mounted in the valve housing and is urged by a spring 24 toward a lip 25 on the opposite wall of the valve chamber and surrounding an outlet 26 therefrom. The valve 23 is preferably provided with an annular facing of vulcanite or similar material to ensure a leak-proof joint between the lip 25 and the valve 23 when the latter is closed.

10 The valve 23 is actuated to lift it from the lip 25 by a stem 28 in loose engagement therewith and projecting through the outlet 26 and a stuffing box 29 which prevents escape of the gas about the stem. The stem is preferably provided with a flattened head, which is adapted to be engaged by a surface arranged in movable contact with the stem, preferably a roller 30. The roller 30 is 15 mounted on a trigger 31, which is pivoted in a bracket 32, and capable of swinging movement to force the stem 28 and the valve 23 backwardly, thus permitting oxidizing gas to flow through the outlet 26 and thence 20 through a passage 33 to the conduit 10. The bracket 32 is preferably a separate part, which is secured to the block 12 by screws 34, to permit removal of the trigger when it is necessary, for example, to repack the stem 25. The trigger 31 is preferably formed with two arms, 35 and 36, the former of which is adapted to be engaged by the fingers in swinging the trigger rearwardly to 30 open the valve, the other arm resting in engagement with the back of the fingers in order that the valve may be readily released when the roller has passed the center and holds the valve in open position.

From the foregoing, it will be understood 40 that the structure described, presents numerous advantages, particularly in its simplicity and the ease with which it may be dismantled for replacement or repair as compared with similar devices heretofore 45 available. By removing the screws 34, the bracket 32 may be withdrawn with the trigger, thus giving access to the packing in the stuffing box 29 and stem 28. The valve housing 22 may also be removed by simply 50 unscrewing it from the block. Since these parts require attention from time to time to ensure maximum efficiency of the apparatus, it is manifest that a blowpipe embodying the features noted, represents a distinct improvement in the art.

55 The operation is equally simple. To open the valve for the purpose of supplying oxidizing gas to the cutting jet, it is necessary only to pull the trigger rearwardly until 60 the roller 30 passes the center. The valve

is thereafter held open without further manipulation of latches or other locking devices until the operator moves the trigger in the opposite direction, when the valve closes under the actuation of the spring 24. 65 The operation may be accomplished without exerting any considerable force on the trigger and the alignment of the cutting jet on the work is not disturbed as it frequently is in the operation of previously known cutting blowpipes.

Various changes may be made in the form and arrangement of the parts without departing from the invention or sacrificing any of its material advantages.

75 I claim:

1. In a cutting blowpipe, the combination including a conduit for oxidizing gas to supply the cutting jet and conduits for oxidizing and combustible gases to supply the 80 heating flames, a casing surrounding the rear portions of the conduits and forming a handle of the blowpipe, a block within the handle having a valve chamber, means for delivering oxidizing gas to the valve chamber, a valve within the valve chamber to control the oxidizing gas for the cutting jet, a valve stem projecting through the handle, and a pivoted trigger having a roller contacting with the stem to actuate the valve 85 when the trigger is turned about its pivot, the pivot of the trigger being offset from the axis of the stem whereby the valve is held in open position when the roller passes the axis.

95 2. In a cutting blowpipe, the combination including a conduit for oxidizing gas to supply the cutting jet and conduits for oxidizing and combustible gases to supply the 100 heating flames, a casing surrounding the rear portions of the conduits and forming a handle of the blowpipe, a block within the handle intermediate the ends thereof and having a valve chamber, means for delivering oxidizing gas to the valve chamber, a valve within the chamber, a stem loosely engaging the valve, a stuffing box surrounding and supporting the stem and means outside the handle for actuating the valve stem, consisting of a removable bracket secured to the 105 block and a trigger pivotally mounted therein and having a roller adapted to contact with the stem, the pivot of the trigger being offset from the axis of the stem whereby the valve is held in open position when the 110 roller passes said axis.

115 In testimony whereof I affix my signature.

EUGENE L. RAGONNET.
